ALEXANDER BENJAMIN KOKERNOT, OF NEW ORLEANS, LOUISIANA.

HAT-PIN.

1,117,858.

Specification of Letters Patent.

Patented Nov. 17, 1914.

Application filed March 25, 1913. Serial No. 756,814.

To all whom it may concern:

Be it known that I, ALEXANDER B. KOKERNOT, a citizen of the United States, residing at New Orleans, Orleans parish and State of Louisiana, have invented a new and useful Hat-Pin, of which the following is a specification.

This invention has reference to improvements in hat pins and its object is to provide 10 a pin of simple construction which may be secured firmly to the hat and at the same time be susceptible of adjustment lengthwise of the part attached to the hat.

The present invention which is an improvement upon the hat pin shown in my application No. 680,209, filed February 27, 1912, for improvements in hat pins, comprises a head member of elongated form 15 with means at one end for attaching it to a hat, and means at the same end for anchoring the pin after attachment, the said head member being of skeleton construction, and to this head member there is applied a shank member having a portion formed to enter

20 the head member and be progressively moved therealong in either direction by a screw action, so that the extent of projection of the shank of the pin may be determined at the will of the operator.

25 The invention will be best understood from a consideration of the following detailed description, taken in connection with the accompanying drawings forming a part of this specification, with the further understanding that while the drawings show a practical form of the invention the latter is not confined to any strict conformity with the showing of the drawings, but may be changed and modified so long as such changes 30 and modifications mark no material departure from the salient features of the invention.

In the drawings:—Figure 1 is an elevation of a pin constructed in accordance with 35 the present invention. Fig. 2 is a perspective view of the shank member shown on a somewhat larger scale than Fig. 1. Fig. 3 is a perspective view of the head member with the anchoring means omitted. Fig. 4 is a perspective view of the anchoring device carried by the head member. Fig. 5 is a section on the line 5—5 of Fig. 1, but drawn on a larger scale. Fig. 6 is a section on the line 6—6 of Fig. 1 and drawn on the 50 scale of Fig. 5. Fig. 7 is an elevation of a

portion of the shank member with some parts shown in section.

The pin is provided with a shank 1 which may be of substantially equal diameter throughout, except at the two ends, one of 60 which is pointed, as shown at 2, and the other of which is reduced and preferably square, as shown at 3, for the reception of a manipulating button 4 adapted to the reduced end 3 and there held by a pin 5 or 65 in any other suitable manner. In contradistinction to the point 2 that end provided with the button 4 may be called the butt end and near this butt end the shank 1 has longitudinal grooves 6 formed therein for 70 the reception of one edge of each of a number of fins or webs 7 disposed about the butt portion of the shank 1 in substantially radial relation thereto, and while the invention is not limited to any particular number of fins 75 or webs 7 it is found that four such fins will answer.

Wound helically about the fins 7 is a strand 8 which may be made of wire of a suitable gage, and this strand is secured to 80 the fins by soldering or otherwise, so as to produce a screw thread of long pitch. In the particular showing of the drawings this screw thread or strand 8 has two and one-half turns, but any particular number of 85 turns is not obligatory and a greater or lesser number of turns may be employed. The pitch of the thread may be such as to make it quick acting, but not so quick acting that a companion member adapted to the screw 90 thread will yield to direct forces tending to move it lengthwise of the thread or to move the thread lengthwise of the companion member.

Admitted to the screw thread 8 is a cage 9 95 made up of a number of wires or bars 10 in substantially parallel relation and disposed in circular series, the drawing showing four such wires, each of a length about that of the webs or fins 7. At one end of the cage 100 or head 9 the wires 10 are connected by a ring 11, while at the other end the wires 10 are connected by a disk 12 which latter has a central passage 13 for the pin shank 1 and at diametrically opposite points at the margins the disk 12 carries spurs 14 each so bent as to have a twist in the same direction as the other in helical relation to the longitudinal axis of the disk 12 away from that face of the latter opposite the face entered 110

by the rods 10. The purpose of the spurs 14 is to enter the body of a hat in a manner similar to a screw, so as to draw the head member 9 into firm engagement with the hat 5 by a twisting movement of the head member 9. Each wire 10 has notches 15 therein so related one to the other as to receive the screw thread strand 8, whereby a twisting movement of the pin shank 1 will cause a 10 progressive movement of the shank lengthwise of the cage or head member 9, and when this head member is fast to a hat the pin shank may be screwed into or unscrewed therefrom to a limited extent determined by 15 the axial length of the head member 9 and of the screw thread strand 8.

Applied to the exterior of the head member or cage 9 is a sleeve 16 having at one end a manipulating flange 17 which may 20 stand radially therefrom and be suitably formed for the application of the fingers of the user, so that this sleeve may be moved longitudinally of the head member 9. At 25 the other end of the sleeve 16 are axially projecting pins 18 the free ends of which may be pointed, and these pins are designed to project through openings 18^a in the disk 12, while a fixed outstanding stud 19 of one of the wires 10 projecting through a longitudinally extended slot 20 in the sleeve 16 30 prevents the said sleeve from rotating and limits its longitudinal movement, so that the pins 18 when the sleeve is moved in one direction will have their pointed ends withdrawn until interior to the outer surface of 35 the disk 12 and when the sleeve 16 is moved in the other direction these pins will project beyond the outer surface of the disk 12 to an extent to enter a sufficient distance into 40 the wall of the hat. If the head or cage 9 be applied to a hat body and then twisted so that the spurs 14 enter the hat it will be thereby locked to the hat, but a movement of the head member about its axis in a reverse direction would cause the unlocking of 45 the head member from the hat and this might quite easily occur. When, however, the sleeve 16 is moved so as to cause the pins 18 to enter the hat body after the head member 50 is locked thereto, then the reverse movement of the head member tending to disconnect the spurs 14 from the hat is prevented, the pins 18 acting as anchoring members. Should, however, it be desired to 55 disconnect the pin from the hat it is simply necessary to withdraw the pins 18 by an appropriate sliding movement of the sleeve 16 when the spurs may be readily disconnected from the hat by a reverse movement of the 60 head 9.

The effective length of the shank 1 is readily determined by unscrewing the shank 1 where extending through the head member 9 to a commensurate extent or screwing it thereinto so far as desired, and the

members may have a sufficiently snug fit to prevent accidental turning of the shank in the head member 9 when the latter is anchored to the hat.

The head member may be fastened to the 70 hat and left there as long as desired, while the pin shank 1 may have its pointed end 2 first extended through the head member 9 until it passes through the opening 13, and then forced through the corresponding portion of the hat body and the hair of the wearer until it engages the other side of the hat body, by which time the screw thread 8 has been passed through the ring 11 and into engagement with the notches 15, whereupon a further progressive movement of the shank 1 is caused by turning the pin shank, thus screwing the threaded butt end of the shank into the head member 9 to such an extent as to cause the point of the pin to project slightly beyond the other side of the hat body for engagement with which the pin entirely traverses the hat and pierces the opposite side thereof.

It is sometimes desirable that the threaded butt end of the pin shank be substantially completely seated in the head member 9 and yet be readily removable therefrom, while at the same time not interfering with the ready determination of the effective or active projection of the pin shank 1 from the head member. To bring this about the pin shank indicated at 1^a in Fig. 7 may be of substantially even diameter throughout, except at the two ends, as in the form shown in Fig. 1, but the grooves 6 are omitted. In place of these grooves there is provided an elongated tube or sleeve 21 which may closely fit the pin shank but not so closely as to prevent movement of the sleeve lengthwise of the pin shank. On the exterior of the tube 21 is a helically disposed web or fin 22 designed to replace the fins 7 and the strand 8 and this helical fin 22 is in effect a screw thread which may fit the grooves 15 and perform the same office as the thread 8. A set screw 23 carried by the tube 21 provides a means whereby the tube may be secured at any point along the pin shank 1^a so that even though the tubular member 21 with its web screw thread 22 be entirely housed within the head 9 the active projection of the pin shank 1^a will be determined by the location of the tube 21 on said pin shank, the said tube being fastened in the 110 desired location by the set screw 23.

The cage or head member 9 and the button 4 may, of course, be provided with any desired kind of ornamentation, but such features do not enter into the present invention and hence no attempt is made to show any ornamentation in the drawings. So far as the usefulness of the invention is concerned the features shown in the drawing are ample besides producing a simple, cheaply con-

structed and highly useful device which may be fixedly secured to a hat without interference with its ready removal, and wherein the effective projection of the pin shank may be readily determined by the user. The pin shank may be made of maximum length and yet be readily adapted to hats of different sizes, so that there need be no dangerous projection of the sharp point of the pin beyond that part of the hat body remote from the head of the pin.

What is claimed is:—

1. A hat pin comprising a head member having means for securing it to the body of a hat, means on the head member and movable independently thereof and coacting with the securing means for anchoring the head member to the body of the hat against the action of twisting forces, and a shank member, the said head member and shank member having coacting screw connections for causing lengthwise movement of the shank member in the head member, on the turning of said shank member, for determining the active projection of the pin shank.
2. A hat pin comprising an elongated head member having means for securing it to the body of a hat, means on and movable lengthwise of the head member and coacting with the securing means for anchoring the head member to the body of a hat against rotative movement, and a shank member movable lengthwise of the head member for determining the active projection of the pin shank, and said head and shank members being coactively constructed to cause the lengthwise movement by a twisting movement of the shank member.
3. A hat pin comprising a head member and a shank member, the head member having at one end means wholly carried by the head member for securing it to a hat, and means also carried by the head member and having a range of movement independently thereof for anchoring the head member to the hat after being secured thereto and the shank member being movable in the head member rotatively and lengthwise thereof for determining the effective projection of the shank member.

4. A hat pin comprising a head member and a shank member, the head member being in the form of a skeleton cage and the shank member having one end formed with a screw thread of long pitch adapted to the interior of the cage and the latter being shaped to coact with the screw thread, said head member being provided at one end with spurs shaped to enter a hat body by a rotative movement of the head member, and a

longitudinally movable device on the head member having pins or spurs movable into the hat body to anchor the head member thereto after the first-named spurs have entered the hat body. 65

5. A hat pin comprising a head member and a shank member with long pitch screw thread connection between them, said shank member being adjustable lengthwise of the head member by a rotative movement of the shank member, and said head member being provided at one end with spurs shaped to enter a hat body by a twisting movement of the head member and with longitudinally movable pins shaped to enter the hat body in the same direction as the length of the head member to anchor the latter after the spurs have entered the hat body. 70

6. A hat pin comprising a head member and a shank member with a long pitch screw connection to permit adjustments of the shank member longitudinally of the head member, said head member being in the form of a cage composed of longitudinal wires connected at the ends, one end connection being provided with spurs shaped to enter the hat body on a twisting movement of the head member and also provided with a longitudinally movable sleeve having pins 90 projecting therefrom in position to enter a hat body to anchor the head member thereto after being secured to the hat body by the spurs. 85

7. A hat pin comprising a head member and a shank member with screw thread connections for the adjustment of the shank member lengthwise of the head member, the portion of the screw thread connections carried by the shank member being adjustable 100 lengthwise of the latter for determining the effective length of the shank member independently of the extent of threaded connection between the two members. 95

8. A hat pin comprising a head member and a shank member with screw thread connections therebetween for the adjustment of the shank member lengthwise of the head member, the screw thread connection carried by the shank member comprising a tubular 110 part having means for securing it to the shank member at different positions therealong and said tubular member having a helical part forming a screw thread for engagement with the head member. 115

In testimony, that I claim the foregoing as my own, I have hereto affixed my signature in the presence of two witnesses.
